ABSTRACT

A soaking pit furnace used for preparing metal ingots or blooms is provided with two sets of heating means, a principal burner means and an auxiliary burner means mounted in the upper portion of one wall of the furnace. The furnace also has an evacuating means in the lower portion of the same wall. The auxiliary heating means can supply only a minor portion of the heat requirement, but is capable of injecting hot gases into the furnace enclosure at a velocity of at least 70 meters per second.

SOAKING PIT FURNACE

BACKGROUND OF THE INVENTION

A substantial proportion of the metallurgical soaking pit furnaces used for heating or temperature equilibration of steel ingots or blooms are of the so-called one-way soaking pit type. In this type of construction, one or more burners are positioned in the front wall of the oven chamber and a vent is also positioned in the front wall underneath the burners. This design leads to low-cost construction and relatively low requirement for space. In view of the large number of oven chambers required for the manufacture of steel, these are frequently decisive factors.

Despite the cited advantages of the one-way soaking pit, it yields only incomplete temperature equilibration in steel ingots. This is a serious difficulty because large temperature differences within a workpiece are unfavorable to the rolling process. Moreover, since there is a minimum temperature which all parts of the ingot must exceed, then the greater the temperature differences in the ingot, the higher the temperature of the hottest portion. Excessively high temperatures cause strong scaling, operating difficulties, and an economic loss due to a drop in the output of steel.

Blocks to be heated are generally placed vertically in the heating chamber. Temperature differences occur most frequently between the tops and bottoms of the pieces. Metallurgists refer to this temperature difference as being between the head and the foot of the ingot. Temperature differences also occur between opposite faces of the blocks where the face turned toward the source of heat is hotter than the opposite face. Bringing all parts of the ingot to a uniform temperature is rendered more difficult by the fact that the blocks may be introduced cold as well as hot.

The temperature of the blocks must be raised rapidly which requires that a large source of heat be used. For temperature equilibration the rate of heat introduction into the chamber need only be about 10 percent of the full capacity of the source of heat. Since, usually, the blocks are hot when introduced into the heating chamber, the rate of heat input into the chamber need only be 10 to 20 percent of the full capacity of the heat source for the most part, and performance during equilibrating the blocks is crucial.

The more uniformly the workpiece is heated, the shorter will be the dwell time in the chamber. Furthermore, heat consumption will be reduced and the output capacity of the system will be increased.

Attempts have been made to improve the heating process in specific directions. Operating according to conventional methods, one or more burners are used, and these are cycled between high and low heat outputs depending on the heat requirement of the system. As is known, the next improvement of this technique consisted of using two or more burners arranged on a front wall of a heating chamber which were shut off in sequence as the head load decreased. In this way the system could be held within a narrower range of temperatures. It was possible to arrange the burners so that the length of the flame, the burning characteristics and the velocity of discharge of the burners could be controlled. Nevertheless, the results achieved by operating as described have proved to be inadequate. At all times uniform and constant regulation is necessary, dwell times in the chambers are too long, and temperature differences are too large.

SUMMARY OF THE INVENTION

It is an object of the invention to provide a soaking pit furnace for heating ingots and blooms to a temperature suitable for further processing, while avoiding substantial temperature differences between different parts of a workpiece.

It is a further object to lower the maximum temperature to which any part of any workpiece is heated while making certain that every part of every workpiece reaches a specific minimum temperature.

It is yet another object to decrease the dwell time of workpieces in the furnace and thereby increase the output per unit of time by the furnace.

It is still another object to provide a method of operating the burners in the soaking pit furnace to achieve the above objects.

Applicant has found that the process of heating up ingots or blooms in a soaking pit furnace can be improved by placing several burners in the front wall of the furnace and controlling these in response to the demand. When the demand is low, only one or two of the burners are put into operation; as the demand increases, more burners are used to supply the heat. This technique is distinguished by the fact that at low demands, the one or two burners used to supply the heat should be capable of supplying not more than 20 percent of the maximum output of all burners operating together.

Moreover, the gas velocity at the orifices or nozzles of the one or two burners should be more than 70 meters per second at full load. This type of arrangement is desirable because the workpieces are generally put into the furnace while hot and consequently the required burner load for the final phases of the heating process is apt to be 20 percent or less. It is consequently advantageous to arrange to have one or two special burners with the characteristics defined above. These special burners may be termed the auxiliary burners or heat-producing means, while the burner which they flank and which produces from 80 to 95 percent of the total heat requirement may be termed the principal burner or heat-producing means.

The auxiliary burner or burners have a function in addition to supplying up to 20 percent of the total heat requirement: this is to cause turbulence in the chamber gases, this turbulence being largely responsible for the excellent temperature equilibration achieved in the furnace, according to the invention. The gas emerging from the auxiliary burner to burners at 70 m/sec. causes turbulence by entraining the atmosphere of the furnace. Gas velocities higher than 90 m/sec. can be achieved by burning the gases of the auxiliary burner or burners in an auxiliary chamber and leading the combustion products into the furnace chamber.

The novel features which are considered as characteristic for the invention are set forth in particular in the appended claims. The invention itself, however, both as to its construction and its method of operation, together with additional objects and advantages thereof, will be best understood from the following description of specific embodiments when read in connection with the accompanying drawing.

BRIEF DESCRIPTION OF THE DRAWING

FIG. 1 shows a horizontal section through the furnace chamber; and

FIG. 2 is a vertical section through the line I—I.

DESCRIPTION OF THE PREFERRED EMBODIMENTS

FIG. 1 shows a rectangular soaking pit furnace 1 having a front wall 1a, a principal burner 2 flanked by auxiliary burners 3 and a back wall 5. The billets are designated by the reference numeral 4.

FIG. 2 is a vertical section along the line I—I. This Figure shows the location of the evacuating means 6 through which the gas in the chamber vents. The Figure also indicates the direction of flow of the gas as shown by the arrows. As the Figure shows, gas enters the furnace through the burners, travels for the most part across the tops of the workpieces to the back wall 5 where it is deflected downward, and then travels across the bottom of the furnace leaving through the vent 6. Though the general course of the gaseous combustion product is as shown in FIG. 2, it will be realized that considerable mixing takes place as a result of the injection of combustion products from burners 3 at high velocity. It follows then that the hot, high velocity combustion gases do not travel merely once across the top of the billets where they give up part of their heat and once across the bottom after reflection

from the back wall 5, but that the gases actually make many passes across the workpieces as a result of entrainment of the chamber atmosphere by the high velocity gases from the auxiliary heating means.

To achieve the above results, it is necessary that the streams from the burners be emitted with the highest possible velocity. As a first approximation, considering the auxiliary burners as free jets, then the velocity at each point in the stream is proportional to the orifice velocity and the orifice diameter. The quantity of heating medium entering the chamber per unit of time, and thereby the quantity of heat introduced, is proportional to the product of the orifice velocity and the square of the orifice diameter. More exact investigation has shown that the stream velocity at any random point in the stream is proportional to the root of the orifice velocity for equal volumes issuing from the orifice that is, for equal input. These considerations show that for effective circulation of the gases in the furnace, the orifice cross section should be small and the velocity at which the gas stream issues, should be high. It can be stated that the higher the stream velocity of the auxiliary burners, the greater will be the effect and the better will be the circulation. Further investigation of this effect has shown that if the auxiliary burner or burners supply no more than 10 percent of the maximum requirements, then the burners can be operated at full load continuously and any decrease in the stream velocity can thereby be avoided.

It has been found that by using a high velocity burner with its own combustion chamber, it becomes possible to introduce the combustion products therefrom at a velocity of 90 m/sec. into the soaking pit furnace chamber. This rate is substantially above that possible when the auxiliary burners are mounted in the front wall 1a on the furnace chamber. It is therefore a particularly favorable mode of construction and operation.

It is an especially favorable construction to locate the principal burner in the upper part of the front wall 1a and centrally with respect to side walls. This principal burner should supply from 85 to 90 percent of the total load. Two auxiliary burners are located at the same level as the principal burner and flank the principal burner on either side.

The auxiliary burners are so constructed that after the initial portion of the heating where the maximum heat input is required, and the heat requirements decrease, that the auxiliary burners can be throttled down. Initially the burners are run at a constant setting and after reaching some minimum level, they are operated on an off-on mode. In this way, the operation of these burners at a rate lower than the minimum at which they can give satisfactory performance is avoided.

Without further analysis, the foregoing will so fully reveal the gist of the present invention that others can by applying current knowledge readily adapt it for various applications without omitting features that, from the standpoint of prior art, fairly constitute essential characteristics of the generic or specific aspects of this invention and, therefore, such adaptations should and are intended to be comprehended within the meaning and range of equivalence of the following claims.

What is claimed as new and desired to be protected by Letters Patent is set forth in the appended claims:

1. In a metallurgical furnace, particularly in a soaking pit, a

- combination comprising wall means defining an enclosure having a portion for reception of a charge; at least one principal and a plurality of auxiliary heating means provided in the region of said wall means for discharging hot gases into said enclosure at a total maximum heating capacity of 100 percent, the combined maximum heating capacity of said plurality of auxiliary heating means being at most equal to 20 percent of the total heating capacity of all of said heating means, and each of said plurality of auxiliary heating means being arranged to discharge hot gases into said enclosure at a velocity of at least 70 meters per second when operated at its maximum heating capacity.
2. A combination as defined in claim 1, wherein each of said heating means comprises at least one fuel burner.
3. A combination as defined in claim 1, wherein at least one of said auxiliary heating means comprises a high velocity burner having a combustion chamber provided with at least one orifice for discharge of hot combustion products into said enclosure at a velocity of at least 90 m/sec.
4. A combination as defined in claim 1, wherein the heating capacity of said auxiliary heating means at least approximates 10 percent of the total heating capacity of all of said heating means.
5. A combination as defined in claim 1, wherein the heat energy output of said auxiliary heating means is constant.
6. A combination as defined in claim 1, wherein said principal heating means comprises at least one fuel burner whose heating capacity constitutes between 85 and 90 percent of the total capacity of said heating means.
7. A combination as defined in claim 1, wherein said auxiliary heating means comprises two fuel burners flanking said principal heating means.
8. A combination as defined in claim 1, wherein the heat energy output of at least one of said heating means is variable.
9. Process of bringing metal workpieces to a required high temperature by means of hot gases, comprising the steps of placing said workpieces in an enclosure; introducing into a first region in said enclosure hot gases in such quantity that such gases supply at least 80 percent of the required heat energy; and introducing into a plurality of additional regions of said enclosure hot gases at a velocity of at least 70 m/sec., whereby the gases introduced at said additional regions supply the remaining heat energy required.
10. Process as defined in claim 9, wherein said hot gases introduced at said additional regions supply up to 10 percent of the heat energy required.
11. Process as defined in claim 9, wherein said hot gases introduced at said additional regions enter said enclosure at a velocity of at least 90 m/sec.
12. Process as defined in claim 9, further comprising the steps of gradually reducing the rate of introduction of hot gases at at least one of said regions when the temperature within said enclosure rises to a predetermined value; and thereupon maintaining constant the rate of introduction of hot gases at said regions.
13. Process as defined in claim 12, further comprising the step of intermittently interrupting the introduction of hot gases at said regions.
